United States Patent Office.

M. M. FOLLETT, OF LAKE CITY, MINNESOTA.

Letters Patent No. 97,899, dated December 14, 1869.

IMPROVED CLOTHES-WRINGER.

The Schedule referred to in these Letters Patent and making part of the same.

To all whom it may concern:

Be it known that I, M. M. FOLLETT, of Lake City, in the county of Wabashaw, and State of Minnesota, have invented a new and improved Clothes-Wringer; and I do hereby declare that the following is a full, clear, and exact description thereof, which will enable others skilled in the art to make and use the same, reference being had to the accompanying drawings, forming part of this specification, in which—

Figure 1 represents a side view, partly in section, of my improved clothes-wringer.

Figure 2 is a vertical transverse section of the same.

Similar letters of reference indicate corresponding parts.

This invention relates to a new apparatus for applying pressure to the rollers of a wringer, with an object of obtaining equal and adjustable power without any danger to the rubber of the rollers, or to the articles to be dried.

The invention consists in the combination of the pressure-spring with a screw-rod, lever, and pressure-rod, all so arranged that the pressure applied will be entirely equal at all times, and adjustable to a considerable degree.

A, in the drawing, is the frame of the wringer;

B, the lower roller, hung in the same; and

C, the upper adjustable roller.

D is the bar, which, with its ends, fits into the slotted side bars of the frame, to press upon the journals of the roller C.

From the bar D projects upward, through the top bar a of the frame, a rod, E.

To the upper surface of the bar a is pivoted a lever, F, and to the under side of the bar a is secured one end of a spring, G.

The free ends of the lever and spring are connected with each other by a rod, H, whose length, that is to say, the distance between the spring and lever, can be regulated by a nut, b.

The lever fits upon the upper end of the rod E, and the spring draws it down upon the said rod, thereby applying the pressure to the rollers. The power of the spring, and consequently, the degree of pressure, is regulated by the nut b.

The apparatus may be modified by being doubled, if desired, although I prefer the arrangement above set forth.

Having thus described my invention,

I claim as new, and desire to secure by Letters Patent—

The combination of the rollers of a wringer, with the pressure-rod E, lever F, spring G, screw-rod H, and nut b, all arranged and operating substantially as herein shown and described.

M. M. FOLLETT.
